DESIGN FOR A BOX

John M. Shields, Chicago, Ill., assignor to F. H. Noble & Co., Chicago, Ill., a corporation of Illinois

Application February 8, 1935, Serial No. 55,301

Term of patent 7 years

To all whom it may concern:

Be it known that I, John M. Shields, a citizen of the United States, residing at Chicago, in the county of Cook, State of Illinois, have invented a new, original, and ornamental Design for Boxes, of which the following is a specification, reference being had to the accompanying drawing, forming a part thereof.

In the drawing Figure 1 is a view in perspective showing the front or upper face of the box, and its front and upper edges adapted to receive a rosary or prayer book, or other article of worship or devotion; Fig. 2 is a face view of front face of the same; Fig. 3 is a view of the front edge of the box, and Fig. 4 a rear view of the same.

I claim:

The ornamental design for a box, substantially as shown.

JOHN M. SHIELDS.
